DESIGN FOR A COMBINED TABLE AND BOOKHOLDER

Meril L. Eckman, Canton, Ohio

Application March 6, 1947, Serial No. 137,396

Term of patent 7 years

(Cl. D33—14)

To all whom it may concern:

Be it known that I, Meril L. Eckman, a citizen of the United States, residing at Canton, in the county of Stark and State of Ohio, have invented a new, original, and ornamental Design for Combined Table and Bookholder, of which the following is a specification, reference being had to the accompanying drawing, forming part thereof.

Fig. 2 is a side elevational view thereof;

Fig. 3 is a front elevational view thereof; and
Fig. 4 is a view in perspective thereof.

I claim:

The ornamental design for a combined table and bookholder, substantially as shown.

MERIL L. ECKMAN.
